(57) **CLAIM**

The ornamental design for a sanitizing device, as shown and described.

DESCRIPTION

FIG. 1 is a three-quarter top perspective view of a sanitizing device;

FIG. 2 is a front elevational view thereof;

FIG. 3 is a rear elevational thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures are for the purpose of illustrating portions of the sanitizing device, which form no part of the claimed design.
